UNITED STATES PATENT OFFICE.

CHARLES BATTELL LOOMIS, OF LEONIA, NEW JERSEY.

DESIGN FOR A PAPER-WEIGHT.

No. 39,934.

Specification for Design.

Patented April 20, 1909.

Application filed February 16, 1909. Serial No. 478,339. Term of patent 3½ years.

To all whom it may concern:

Be it known that I, CHARLES BATTELL LOOMIS, a citizen of the United States, residing in Leonia, in the county of Bergen and State of New Jersey, have invented a new, original, and ornamental Design for Paper-Weights, of which the following is a specification, reference being had to the accompanying drawing, forming part thereof.

The figure represents a side view of a paper-weight showing my new design.

I claim:

The ornamental design for a paper-weight, as shown.

CHARLES BATTELL LOOMIS.
